UNITED STATES PATENT OFFICE

ARTHUR RITSCHER, OF DRESDEN-LAUBEGAST, GERMANY, ASSIGNOR TO UNITED CIGARETTE MACHINE COMPANY, AKTIENGESELLSCHAFT, OF DRESDEN, GERMANY

APPARATUS FOR USE WITH PACKING MACHINES FOR FEEDING AND ADJUSTING CIGARETTES

Application filed March 26, 1930, Serial No. 439,169, and in Germany March 22, 1929.

In rod cigarette machines for the production of cigarettes with lettering or with tips, it is customary to apply the printing or the tipping material to the cigarette paper in such a way that two tips or letterings are always in juxtaposition, so that, when the cigarette is cut through, the knife passes through the tipping material extending over two cigarettes, or, if there are no tips, the knife passes between the two letterings applied opposite each other. The result of this is that the seam on the back of the cigarettes points in a different direction, according to whether it is a question of the first or the second of two consecutive cigarettes, because, the method of manufacture resulting in two cigarettes, always being joined at their tips, the second cigarette in each case must necessarily be reversed, in order that the tips shall all be arranged in the same direction.

Now, it has recently been suggested that while conveying the cigarettes to the packing machine, the cigarettes having their lettering downward, for example with the seam upwards, should be turned up by engaging a finger in the seam, which finger then either turns the cigarette directly or only begins to turn it, or releases a relay or the like which in its turn operates a turning device.

If, for example, the cigarettes pass before the finger in any fashion, their seam pointing in different directions, it is therefore evident that the finger can only engage those cigarettes which, when moving forward have the front edge of the paper overlap to the fore, whereas of course, those cigarettes in respect of which the said front edge points backwards in relation to the direction of movement, pass the finger and are not acted upon by it.

The present invention purports to remedy this disadvantage. To this effect, the apparatus in cigarette rod machines is used, whereby two cigarettes which, when in the rod are connected by their tips, are deposited on separate conveyor bands or conveyed to separate compartments, in order that one of these sorts can, before the packing opera-

tion, be brought into the same direction as the other sorts by a turn of 180°.

In accordance with the invention, the two kinds of cigarettes are handled by separate conveying devices and conveyed to a common conveying band from both sides and in each of these conveying devices, a finger device is incorporated in the usual manner. The result of this is that each cigarette engages the finger in the proper way, being righted as it should be.

At the same time, care must be taken that the cigarettes conveyed from both sides on to the common band lie in such a manner that the beginning of the lettering can always be read. This, according to the invention, is obtained by designing a device whereby the cigarettes, according to whether they are conveyed from one side or from the other, are, while being adjusted into the tilted position in which they lie in packing, turned in one direction or the other.

The drawings illustrate one form of the invention by way of example, viz.

Fig. 1 is a part of a cigarette rod, showing a number of cigarettes connected together and a cross section of same.

Fig. 2 shows two cigarettes which were immediately adjacent in the rod and have now been cut, and also the cross section of same.

Fig. 3 illustrates an open box of cigarettes, and shows how the cigarettes should be arranged in the box.

Fig. 4 illustrates diagrammatically in plan the conveying of the cigarettes to the packing machine.

Fig. 5 is a diagrammatic elevation of the above.

Fig. 6 illustrates the apparatus for tilting the cigarettes conveyed from one side and

Fig. 7 the apparatus for tilting the cigarettes conveyed from the other side.

Fig. 8 shows another form of the invention for tilting the cigarettes and

Fig. 9 is a front view of Fig. 8.

As can be seen from Fig. 1, the cigarette rod consists of an endless tube 2 filled with tobacco and provided at definite intervals with tipping material 3, the rod also bearing

lettering 4. The tipping material 3 is wide enough to correspond to two cigarettes and the letterings of two adjacent cigarettes are directed in opposite directions. The rod is cut through the place marked by a dotted line 5, and the result is the two cigarettes 6 and 7 as shown in Fig. 2. As the seam in the rod, as shown in Fig. 1 of course runs throughout in the same direction on the back, (this can be seen in the sectional view) therefore, as can be seen in the sectional view corresponding to Fig. 2, cigarette having been turned through 180°, the seam is bound to point in a different direction, that is to say, in the case of cigarette 6 as can be seen from the cross section, the front edge of the seam points to the right, while in cigarette 7 on the contrary it points to the left. If, therefore, the cigarettes 6 and 7 are fed in any fashion, the finger which, designed in the usual way and engaging the cigarette, reverses, that is to say, turns upwards the cigarettes with downward pointing lettering, only engages those seams the front edge of the overlapping part which faces the finger. In accordance with the invention the two kinds of cigarettes are therefore handled separately. Moreover, these two kinds of cigarettes as already stated are already separated automatically by the cigarette rod machine, and in accordance with the invention, as shown diagrammatically in Fig. 4, the cigarettes of one kind being conveyed to a common conveyor band 10 by conveying devices 8 running from left to right, and the other kind of cigarette by conveying devices 9 running from right to left. Each of the conveying devices 8 and 9 has its own turning device with finger, as can be seen from the diagrammatic Fig. 5, 11 being the finger of conveying devices 8 and pointing in a direction opposite to that of the finger 12 belonging to the conveying device 9. All cigarettes are therefore turned into the correct position and can be conveyed in that position to the common conveying device 10.

Cigarette-turning devices having fingers engaging the seam of the cigarettes lying in an incorrect position with the seam upward are fully disclosed in U. S. patent applications Serial Nos. 376,068 and 472,444 and in the U. S. Patent No. 1,777,361 so that a further description of the functions and operation of the members 11 and 12 seem unnecessary.

As is well known, cigarettes which are flattened, are placed in the boxes slantwise and they must be arranged as shown in Fig. 3 in such a way that the beginning of the lettering, that is to say, the first letters, can be read. In order to achieve this, the usual devices for pivoting the cigarettes into the tilted position are also fitted in the conveying devices 8 and 9. These devices however, as shown in Figs. 6 and 7 are so designed

that, irrespective of the side from which the cigarettes are fed, they turn these in such a manner that the first letter of the lettering is always upwards. Fig. 6 shows the device for the cigarettes fed from the left, that is to say, by the conveying device 8. The conveying device is here, as in Fig. 5, shown in the form of a chain 8 which is provided with carriers 13 on which the cigarettes are placed. While the cigarettes are still in the recesses of the carriers 13 they run over a rail 14 which is arranged between two correlated chains of each conveying device.

The parts of the guide rail which come in contact with the cigarettes are placed somewhat higher than the bottom of the recesses so that the cigarettes in the recesses are moved along over the rail 14, this results in friction on rail 14, the cigarettes are held back at their lower end whilst the upper part of the recesses comes into contact with the higher parts of the cigarettes and inclines these somewhat as shown in Fig. 1.

The cigarettes are carried away by the chain recesses 13 on to an adjusting bar 15 which has a rough surface 16. In this connection the cigarettes are further raised through the friction against the surface on which they rest and the cigarettes are then inclined in such a way that they engage the adjusting bar 15 on the one hand and also a further bar or cover rail 17 arranged above the cigarette path. The cover rail 17 preventing the cigarettes from assuming too inclined a position.

The rail 17 can be adjusted vertically by means of a set screw 18. On the machine frame there is a lever 20 connected at 19 and this lever in turn is connected to a second lever 22 by means of a pin 21, so that the two parts 20 and 22, form, so to speak, a double pendulum. While the cigarettes are pushed forward between the rails 15 and 17 the part 20 assumes a position behind or on the particular cigarette which has been pushed forward by the relative chain link 13 and keeps it from falling back. The cigarette 26 delivered by the chain links 13 pushes the preceding cigarettes further onwards, so that they arrive under part 22 of the pendulum, which secures the collected cigarettes.

Above the conveying path there is a chain 23 fitted with carriers 23, which runs over the chain roller 25. The carriers 23 place themselves against the batch of cigarettes conveyed previously and carry same along with them; they convey them between the rail 24 and the rail 15 towards the place where packing is effected.

The cigarettes are therefore subjected in this device to a clockwise rotation, that is to say, to the right.

The cigarettes fed from the other side, in order that the first letter of the lettering should again point upwards, must also turn

clockwise. This however is not possible if the apparatus shown in Fig. 6 is also to be used for the cigarettes fed from the right. That is why the tilting device shown in Fig. 7 has been provided. Here the conveying chains 9 of which, as is known, a pair always run next to each other, are equally provided with holding recesses 26^a. In that device, however, there is no rail 14 as in Fig. 6; actually the cigarettes are conveyed between a fixed guiding surface 27^a which is placed approximately level with the bottom of the recesses and a cover rail 28, the position of which can also be adjusted by means of a set screw 29. The cover rail 28 has an inclined surface 30, whilst a rail 31 arranged at the end of the path 27^a and forming an extension of the latter has at the beginning an appropriately designed sloping path, which is later followed by a horizontal path, as in the case in rail 28.

The cigarettes in this case also are pushed forward by the carriers 32, in the guide formed between the paths 27^a and 31 on the one hand and 28 on the other, directly the recesses 26^a release them. By gliding through the oblique guide the cigarettes are raised edge first. Therefore in this instance also they are turned clockwise and are formed into a row as shown in Fig. 7. The cigarettes thus upraised and righted properly are pushed into layers by the carrier 23 or 32 from left and from right on the common conveyor band indicated in Fig. 4. The said conveyor band conducting them to the packing device.

The oblique upward pointed cigarette guide, preferably as shown in Fig. 7, has a certain disadvantage in so far that while they are being conveyed in the unstable oblique position, the cigarettes immediately in front of the carrier are in a more inclined position than the other cigarettes of the row concerned, so that therefore all the cigarettes are not in the same position, and when they are laid into the box, difficulties arise. For that reason, one can adopt instead of the apparatus shown in Fig. 7, the apparatus as Figs. 8 and 9, in which for the purpose of upraising the cigarettes conveyed upper edge first, the said cigarettes are held down by a weak holding spring, on the flat conveying path connected to the conveying chain, in order that the elevated rear wall of the recess with which the links of the conveyor chain are provided, on moving downwards from the path of the cigarettes, depresses the rear end of the cigarette in the conveying device, so that it is raised with the front end in the conveying device, whereupon the cigarettes secured in that position by means of pawls, springs or the like are conveyed further along.

In the form of the invention in accordance with Figs. 8 and 9, the cigarettes are fed on

a conveying chain, which essentially consists of links *a* made in the ordinary way and connected together by joints.

At the end of the chain path, that is to say, at the point where it moves downwards and out of the feed path of the cigarettes, a conveying plate *P* is connected to it and the cigarettes are first laid down flat on this plate by a pawl *b* arranged on its upper side, and held down against this plate by means of the weak holding spring *c*. As soon as the cigarettes lie on the plate *P*, the rear edge *a¹* of the plate on the chain links *a* acts upon the cigarette and inclines it, as shown in the case of the cigarette *h* in the drawings, and in such a manner that the end which comes first in the conveying device is raised. During their further progress the cigarettes then encounter a number of pawls or the like *e* arranged as pendulums. These pawls or pendulums hold the cigarettes inclined and the latter push them out of the path as is shown in Fig. 8 in the case of the first pawl. Directly the required number of cigarettes is collected on the plate *P*, these cigarettes are conveyed further on by a carrier *h*, which carrier is fitted to an upper conveying chain *h¹*. The carrier *h* conveys the cigarettes further on to the conveying device *m* serving for the transversal transport. On this path the cigarettes are held by the combs *f*, the teeth of which consist of very light steel leaf springs *g* which, when the cigarettes pass through, assume the bent shape shown for the middle teeth and cease to be inclined straight towards the oncoming cigarettes—which is the position shown for the first and last tooth. The springs must be very weak so as not to compress or damage the cigarettes. Finally the cigarettes arrive under a brush *i*, which is placed above the transverse conveying device *m*, and can now be conveyed by the latter further on into the boxes in order to be deposited there.

Naturally, the device can also be designed on other lines. In particular the cigarettes can be held during their progress by other means also. One could therefore arrange brush-like or pawl-like devices or the like instead of the combs *f*, *g*.

The invention moreover is not confined to the special means for raising the cigarettes or for turning the cigarettes into the proper position. In fact, in addition to the devices described, other known or new devices intended for that purpose can also be used.

I claim:

1. Apparatus for adjustably feeding cigarettes from a cigarette-making machine to a packing machine comprising in combination with the conveyor running from the cigarette-making machine to the packing machine two conveying means arranged on opposite sides of said conveyor, and two adjusting apparatus, each one being connected and

cooperating with one of said conveying means and including means adapted to engage the seam of the cigarettes lying with the seam upwards for tilting them.

2. Apparatus for adjustably feeding cigarettes from cigarette-making machine to a packing machine comprising in combination with the conveyor running from the cigarette-making machine to the packing machine two conveying means arranged on opposite sides of said conveyor, and two adjusting apparatus, each one being connected and cooperating with one of said conveying means and including means adapted to engage the seam of the cigarettes lying with the seam upwards for tilting them in the same direction of rotation.

3. Apparatus according to claim 1, in which one of said adjusting apparatus comprises a rough base, and carriers engaging the cigarettes on a point above said base and conveying them thereover, thereby producing a torque tending to raise one side of the cigarettes.

4. Apparatus according to claim 1, in which one of said adjusting apparatus comprises rails having a rough surface, and carriers engaging the cigarettes on a point above said rails and conveying them thereover, thereby producing a torque tending to raise one side of the cigarettes.

5. Apparatus according to claim 1 in which one of said adjusting apparatus comprises a rough base, and carriers engaging the cigarettes on a point above said base and conveying them thereover, thereby producing a torque tending to raise one side of the cigarettes; in combination with a cover bar arranged above said rough base and limiting the tilt of the cigarettes.

6. Apparatus according to claim 1, in which one of said adjusting apparatus comprises a rough base, and carriers engaging the cigarettes on a point above said base and conveying them thereover, thereby producing a torque tending to raise one side of the cigarettes; in combination with a cover bar arranged above said rough base and limiting the tilt of the cigarettes, two levers also arranged above said base pivotally connected with each other and adapted to hold a definite number of cigarettes, and a conveying member moving along said cover bar and adapted to seize said cigarettes held by said levers.

7. Apparatus according to claim 1, in which one of said adjusting apparatus comprises a rough base, and carriers engaging the cigarettes on a point above said base and conveying them thereover, thereby producing a torque tending to raise one side of the cigarettes; in combination with a cover bar arranged above said rough base and limiting the tilt of the cigarettes, two levers also arranged above said base pivotally connected

with each other and adapted to hold a definite number of cigarettes, a conveying member moving along said cover bar, and stops arranged on and moving with said conveying member and adapted alternately to seize 70 said cigarettes held by said levers.

8. Apparatus according to claim 1, in which one of said adjusting apparatus comprises a slanting upward-directed guide guiding the upward edge of the cigarettes 75 first in relation to the direction of their movement.

9. Apparatus for adjustably feeding cigarettes from a cigarette-making machine to a packing machine comprising in combination with the conveyor running from the cigarette-making machine to the packing machine, conveying means arranged on one side of said conveyor and consisting of a chain composed of links for holding the cigarettes; 80 a conveying path forming a continuation of said chain; a spring holding the cigarettes down on said path; raised rear walls on said links adapted to depress the rear side of the cigarettes passing from the links to the conveying path, thereby raising their front sides in relation to the direction of feed; and means for securing the cigarettes when further conveyed in that position arranged 85 along and above said path.

10. Apparatus for adjustably feeding cigarettes from a cigarette-making machine to a packing machine comprising in combination with the conveyor running from the cigarette-making machine to the packing machine, conveying means arranged on one side of said conveyor and consisting of a chain composed of links for holding the cigarettes; 100 a conveying path forming a continuation of said chain; a spring holding the cigarettes down on said path; raised rear walls on said links adapted to depress the rear side of the cigarettes passing from the links to the path, thereby raising their front sides in relation to the direction of feed; and pendulum-like arranged pawls mounted along and above said path and securing the cigarettes 105 in that position when further conveyed.

11. Apparatus for adjustably feeding cigarettes from a cigarette-making machine to a packing machine comprising in combination with the conveyor running from the cigarette-making machine to the packing machine, conveying means arranged on one side of said conveyor and consisting of a 110 chain composed of links for holding the cigarettes; a conveying path forming a continuation of said chain; a spring holding the cigarettes down on said path; raised rear walls on said links adapted to depress the rear side of the cigarettes passing from the links to the path, thereby raising their front sides in relation to the direction of feed; 115 pendulum-like arranged pawls mounted along and above said path and securing the cigarettes 120 in that position when further conveyed.

12. Apparatus for adjustably feeding cigarettes from a cigarette-making machine to a packing machine comprising in combination with the conveyor running from the cigarette-making machine to the packing machine, conveying means arranged on one side of said conveyor and consisting of a 125 chain composed of links for holding the cigarettes; a conveying path forming a continuation of said chain; a spring holding the cigarettes down on said path; raised rear walls on said links adapted to depress the rear side of the cigarettes passing from the links to the path, thereby raising their front sides in relation to the direction of feed; pendulum-like arranged pawls mounted along and above said path and securing the 130

cigarettes in that position when further conveyed; and combs, the teeth of which consist of weak leaf springs arranged on a continuation of said pawls above said path and adapted to hold the fed cigarettes in their
6 upraised position.

In testimony whereof I affix my signature.
ARTHUR RITSCHER.
